UNITED STATES PATENT OFFICE.

JOHN C. GILLETTE, OF LAKEWOOD, OHIO, ASSIGNOR, BY MESNE ASSIGNMENTS, TO NATIONAL CARBON COMPANY, INC., A CORPORATION OF NEW YORK.

APPARATUS FOR APPLYING BINDING-POSTS TO DRY CELLS.

1,385,783.

Specification of Letters Patent. Patented July 26, 1921.

Application filed September 20, 1916. Serial No. 121,909.

To all whom it may concern:

Be it known that I, JOHN C. GILLETTE, a citizen of the United States, residing at Lakewood, in the county of Cuyahoga and State of Ohio, have invented a certain new and useful Improvement in Apparatus for Applying Binding-Posts to Dry Cells, of which the following is a full, clear, and exact description.

10 This invention relates to apparatus for making dry cells, and particularly to means for performing the operations on the dry cell container known as "scratching" and "posting". The former term relates to 15 abrading or grinding a spot near the upper edge of the container, and the latter to applying and soldering the binding post to the container at the buffed spot.

The invention also relates to a conveyer 20 adapted to transfer dry cells to various operative positions during the process of manufacture.

Another object is to construct a holder 25 for conveniently supporting a dry cell container upon a conveyer.

A further object is to perform the "scratching" and "posting" operations automatically.

The usual method of performing the operations to which this invention relates, consists in transferring the cells from one operator or machine to the next in trucks, or in having the workmen proceed from truck to truck. This method involves considerable confusion, requires a large floor space 30 and necessitates the employment of a large number of operators. My invention reduces these disadvantages to a minimum.

In the accompanying drawings, an arrangement is shown for facilitating the above operations, in which:

Figure 1 is a front view of the entire machine with certain parts broken away and others omitted, to permit more complete 45 illustration.

Fig. 2 is a plan view looking downward on Fig. 1 with corresponding portions broken away.

Fig. 3 is a plan view of one of the cell 50 holders and a portion of the conveyer chain.

Fig. 4 is a side view of the holder illustrated in Fig. 3 with a cell in position.

Fig. 5 is an end view of Fig. 4 looking from the left.

55 Fig. 6 is a plan view of two cell holders

of a modified form which are connected directly together to eliminate the conveyer chain.

Fig. 7 is a cross sectional view on the line A—A of Fig. 6 showing in addition 60 the supporting members.

Fig. 8 is a partial section on the line B—B of Fig. 1 with a cell container placed in position.

Fig. 9 is a partial section on the line 65 C—C of Fig. 2.

Fig. 10 is a view of certain parts adjacent to the scratch brush.

Fig. 11 is a view corresponding to that of Fig. 10 with the cells moved into a different position.

Fig. 12 is an enlarged cross section on the line D—D of Fig. 1.

Fig. 13 is a view of the parts shown in Fig. 12 looking toward the left.

Fig. 14 is a cross section on the line E—E of Fig. 12 looking toward the left.

Fig. 15 is a cross section on the line F—F of Fig. 12 looking toward the left.

Fig. 16 is a view of the soldering iron 80 and container in the central position of the soldering stroke.

Fig. 17 is a view of the soldering iron and container at the end of the soldering operation.

Fig. 18 is a detail view of the spring bearing of the soldering iron.

Fig. 19 shows a front view of a terminal to be soldered to the container.

Fig. 20 is a perspective view of a container with a binding post soldered thereto.

Figs. 21, 22 and 23 are detail views of a portion of the apparatus near the left hand end of Figs. 1 and 2, showing the cans in successive operative positions.

Fig. 24 is a detail sectional view of portions of the apparatus on the line G—G of Fig. 1.

In the various figures of the drawings, the same reference characters will be used in 100 all of the figures to designate corresponding parts referred to in the following description. A framework 1 is built up in a suitable manner to support the different parts of the apparatus. Two horizontal 105 members 8 and 9, secured to the uprights 2, 3, 4 and 5, have grooved or rabbeted portions 6 and 7 adapted to act as a track for the endless chain conveyer 10.

Sprocket wheels 11, 12, 13 and 14 are 110

mounted on suitable shafts at the ends of the apparatus to carry the conveyer chain 10. These shafts turn in bearings shown conventionally in the drawings. Screw 15 permits of adjusting the tension of the chain by moving the bearing of sprocket wheel 11 on the block 16 shown at the upper right hand corner of Fig. 1. Since the operators who perform certain work on the cells sit alongside the apparatus, the lower part of the conveyer is inclosed in a box or frame 17, as a precaution against accidents.

A driving pulley 18 fastened to the shaft of the wheel 12 is connected to any source 15 of power to move the chain 10.

Detail views of the particular form of conveyer chain are shown in Figs. 3, 4 and 5. It consists of two kinds of links 19 and 20, having their extremities adapted to be hooked together as shown in Fig. 5. Each link 19 has two supporting wings 21 to which is attached a strip 22 having notched can supports 23, 24 secured thereto. Support 24 has a projecting horn 25 with a removable top member 26 which is attached to the lower part of the horn by means of a screw 27 passing through lugs 28. The removable top member has a notch 29 at its free end for a purpose to be referred to later. When can 30 is placed in the supports the upper edge of the open end is adjacent the notch.

In Figs. 6 and 7 a modified form of can carrier is illustrated which eliminates the use of a conveyer chain. This carrier consists of a number of identical cast iron holders 31 having notched can supports 23 and 24, similar to those of Figs. 3, 4 and 5. To permit these holders to be connected together by means of pins 32, each holder is provided with eight integral lugs projecting downward, four being located on each side. Two outer lugs 33 on one side are approximately flush with the ends and are adapted to cooperate with two outer lugs 34 on the other side. These are spaced from the ends a distance approximately equal to the width of lugs 33 so that when lugs 34 are placed within lugs 33 a pin 32 may be passed through openings 35 cut in each lug. In a similar manner a pair of inner lugs 36 cooperates with a second pair of inner lugs 37. A roller 38 placed between lugs 36 is mounted on the pin 32 which will be passed through suitable openings 35 in all eight adjoining lugs and through the roller in order to connect two adjacent can supports together. The number of holders required to form the carrier will be connected up in this manner. The holders have a projecting horn 25 provided with a removable top member 26 adapted to be fastened to the horn by means of a screw 27. Different shaped top members may be attached to the horn 25 to accommodate various types of binding

posts. A cylindrical member 39, for a purpose to be mentioned later, will be attached to the end adjacent the horn. A stop 40 is provided at the horn end to prevent the cans from being moved too far toward the horn.

For this type of carrier a central support 41 will be provided for the rollers 38. The horizontal members 8, 9 will serve to prevent the holders from being unbalanced when the force is applied to either end. Normally, however, the lugs 33 and 34 will not slide on the horizontal members, but the carrier will be balanced on the rollers 38. The teeth of sprocket wheels 11, 12, 13 and 14 will fit between the rollers when the carrier moves around them.

To enable the cells 30 to be properly placed on the can seats a sheet metal stop 42 (see particularly Fig. 8) is attached to the frame at the loading end. At the other end of the can a spring 43 attached to a projection 44 of the member 9, engages the bottom of the cell to move it against the face of the stop 42 to maintain the open end of the can the correct distance from the horn 26.

The scratching device (Figs. 1, 2, 9, 10 and 11), consisting of a buffing wheel 45 containing an abrasive, is mounted on a shaft 46 and driven by a belt 47. The shaft 46 is carried by bearings in two arms 48 which project from a sleeve 49 of shaft 50. The belt 47 passes around a pulley 51 which can be moved by means of adjusting wheels 52 and grooved blocks 53 to adjust the height of the buffing wheel as it wears down. The weight of the buffing wheel 45 and arms 48 maintains the belt tight. For stopping the rotation of the buffing wheel idle pulleys 54 and 55 are provided as shown in Fig. 2.

A spring 56 attached to the frame and parallel to the chain is adapted to raise each can into contact with the rotating brush 45 when it passes thereunder. As will be seen in Fig. 10, the spring 56 is placed just above the strips 22 and below the cans 30. Near the rotating brush the strip has a bend 57 and a lifting end 58. The horizontal distance from the point of the bend to the rotating brush is practically the same as the distance between the centers of adjacent cells.

The post 59 (Fig. 19) for a dry cell has a slotted base 60 adapted to fit the open end of the can and a threaded end 61 for the terminal nut.

Mechanism for soldering the posts 59 to the cells, located near the uprights 4 and 5 of Fig. 1, is illustrated in Figs. 12 to 18. The movable parts are operated by the movement of the strips 22 which engage a star wheel 63 having six projecting arms 64. Bearings 64 attached to the lower surface of the horizontal members 8 and 9 support the star wheel shaft 62 which has a bevel gear 65 at one end. The bevel gear 65 meshes with a second

bevel gear 66 on a vertical shaft 67. A collar 68 resting on projection 69 provides the supporting means for the vertical shaft 67. A second vertical shaft 70 (Fig. 2) is similarly supported by a collar 71 (Fig. 1) and is driven from shaft 67 by means of gears 72 and 73 which mesh together rather loosely. Pulley wheels 74 and 75 having a concave milled surface are fastened to the shafts 67 and 70 respectively and are of approximately the same diameter as the corresponding gear wheels 72 and 73. To keep the gears 72 and 73 meshed and wheels 74 and 75 in contact, a spring 76 is attached to 10 their upper ends. A self fluxing solder such as the wire 77 is drawn from a reel 78 through the space between the milled concave wheels 74 and 75. The strip of solder is drawn over a guide 79 projecting from the 20 member 69.

The arrangement described heretofore constitutes the solder feeding mechanism which is operated in conjunction with a device for reciprocating a soldering iron, through 25 the star wheel shaft 62. At the end of the shaft opposite to the bevel gear a driving gear 80 meshes with a pinion 81 on a countershaft 82. If a star wheel is used having six arms 63, the revolutions of the 30 pinion will be three times the number of revolutions of the gear 80. A rotating arm 83 placed at the end of the countershaft 82 has a pin 84 which moves in a slot 85 of an arm 86. The rotary movement of the arm 35 83 produces a reciprocating movement of slotted arm 86 and a soldering iron 89 attached thereto. The soldering iron is heated in any convenient manner, as by burning gas admitted through a flexible tube 90 into 40 a hollow space in the iron. For purposes to be referred to hereafter, the soldering tool has a notch 91 at its point. The shaft 87 carrying the soldering iron 89 and reciprocating arm 88, is adapted to be moved 45 up and down vertically by bearings 92 mounted between springs 93 (Fig. 18) and 50 slidable in slots 94 in the standards 95 and 96. The vertical height of the bearings in the standards is controlled by a cam 97 on 55 shaft 62 which raises and lowers the reciprocating shaft 87 through arm 98 loosely suspended therefrom. A vertical slot 99 is cut in a portion of the arm to dodge the counter-shaft 82 which passes therethrough and permits the arm to move only in a vertical direction. Collars 100 are fitted on the countershaft 82 to prevent the arm 98 from sliding out of engagement with the cam.

The arrangement as described is adapted 60 to solder only every other post as will be further explained hereafter. The mechanism will therefore be duplicated at some point of the machine in proximity to the first soldering device, as is indicated diagrammatically by the soldering iron 101.

In soldering the base of the post to the can, the soldering material sometimes bridges the gap between the post and the end of the horn or neck 26. To loosen this, any sort of a hammer may be used, such as a spring 70 102 (Figs. 19, 20 and 21) having a projecting end 103 arranged at a proper height to engage the outer point of the horns 26 as they move successively past this point. When the ends are free from the horn they 75 spring inward against the cells and hammer them away from the horn a sufficient distance to loosen the post from the horn.

The unloading is accomplished by a drum 104 driven by means of chain 105 and 80 sprocket wheels 106 and 107. The drum 104 is divided into a number of sectors by means of projecting pins 108 so that the angle of each sector is sufficient to receive a cell. After turning through an angle, represented 85 approximately by the line G—G, the cells are removed from the drum by a twister consisting of fingers or strips 109 and 110 which lie between the radial fingers 108. These finger strips, together with the base 90 111, form a passage gradually changing in direction from horizontal to vertical, so that the cells are delivered to the endless belt 112 in a vertical position where operators can add disks, sealing mixture, etc., to complete them. 95

A tapered sheet metal chute 113 supported on a table 114, receives the cells from the twister and delivers them to a moving platform built up from a number of wooden 100 strips 115 attached to a belt 112. The conveyer or platform is provided with a spring 116 to pack the cells together.

In view of the preceding description, the operation will be but briefly described. The 105 cells will be placed on the notched supports 23, 24 of the carriers and located in the proper position by the action of the spring 43 pressing the open end of the can against the sheet metal stop 42. The cells will be 110 carried along as the conveyer is moved in the direction of the arrows, the strips 22 sliding in the rabbets 6 and 7 of the horizontal bed formed by members 8, 9. When no strip is directly under the rotating brush 115 45 (Fig. 8) the metal strip 56 assumes a position in which none of the cells are raised. When the strips move along to the position of Fig. 9, a cell is directly under the brush and the first strip to the right of the 120 brush engages the bend 57 of the stationary strip 56. This raises the end 58 to a sufficient height to lift the can, which is under the brush, into contact with it. The open end will be tilted up against the brush only 125 for the brief interval during which the bend 57 rides on the strip 22.

The foregoing operation prepares the surface for soldering and also indicates to the operator where the post 59 should be placed. 130

The posts are fitted by hand to the moving cans by one or more operators, with the slot on the edge of the can and the threaded end of the post in the slot 29 of the horn 26 5 to hold it in place. The speed at which the chain is moved may be such that one operator can fit the posts thereto, but I prefer to have three posting operators because one operator can apply the cells to the feeding 10 end with sufficient rapidity to keep three posters busy. Accordingly, each operator applies a post to every third cell.

When the strips 22 approach the soldering mechanism, they engage the six star 15 wheel projections 63 successively. By making them of the proper length, one arm is always in engagement with a strip and remains so until the next strip and arm are in contact. With the modified carrier of Figs. 20 6 and 7 the cylinder 39 will engage the projections 63 of the star wheel. The rotation of the star wheel and shaft 62 is therefore approximately uniform although this is not essential. The rotation of the wheel gradually 25 feeds soldering material 77 from the reel 78 by transmitting rotation to the milled wheels 74 and 75 through the bevel gears 65 and 66 and the gears 72 and 73. The pressure of the spring 76 causes the milled or 30 roughened surfaces of the wheels to grip the solder 77 and feed it forward over the ledge 79 through a tubular guide 117 in position to be melted by contact with the soldering tool.

35 While the solder is being slowly moved forward at the desired rate, the gear ratio of gears 80 and 81 will cause the shaft 82 and pin 84 to rotate through one revolution while the shaft 62 rotates through one third 40 of a revolution. One complete revolution of pin 84 is required for the soldering and return of the tool and during this period the conveyer moves through a distance equal to twice the distance between the centers of 45 adjacent cans. Since only one post is soldered during this time it will be evident that another soldering mechanism 101 must be used in conjunction therewith. One-half of this complete period is consumed for the soldering operation and the soldering tool is maintained in contact with the post while the can moves through a distance equal to the distance between cans.

In the central position as in Figs. 12, 14, 55 15 and 16, the notch 91 of the soldering tool 89 fits over the post which gives a better soldering action because the surface of contact is greater. In this position the soldering tool has already melted the soldering material necessary for the operation by having rubbed the projecting solder 77, and one-half of the soldering period has elapsed. Starting at this point the operation is as follows:—While the shaft 82 rotates together 60 with the arm 83 and pin 84 through

90°, the slotted arm 86 is moved by the pin to the position shown in Fig. 13. The soldering tool 89 is turned through an equal angle and the horizontal component of this angular movement of arm 88 is equal to the 70 horizontal movement of the cans. As shown in Fig. 17, the soldering iron may also be maintained in contact at all intermediate points by the use of suitable specially shaped gears. However, in the present instance, 75 circular gears are shown because with the combination of the short arc of movement of the slotted arm 86, with the star wheel drive, the soldering tool 89 is moved in approximately uniform straight line motion 80 the same as the cans. To prevent the tool from being raised from the post as the soldering tool swings upward, the shaft 87 is lowered by the coöperation of the cam contact arm 98 with the cam 97. This cam will 85 turn through an angle of 30° while the shaft 82 turns through 90°. During this period the shaft 87 of the soldering tool will be lowered by suitably shaping cam 97 and the arm 98 which adjusts the shaft will drop, 90 the bearings 92 meanwhile sliding in the slots 94. The movement of the arm will be straight up and down because the coöperation between the slot 99 and the shaft 82 prevents any rotary movement. 95

During the next 180° of rotation of the arm 83, the tool is raised from the post and returned to the starting position. The raising of the tool from the can is accomplished primarily by the cam 97 and arm 98, but 100 at the beginning and end of a stroke is assisted by the rotary movement of the soldering tool. The combined action during this one-half revolution of the arm will maintain the tool out of engagement with a post 105 while one can passes under the soldering device. This skipped can will be soldered by the same kind of soldering device spaced a short distance from the first soldering mechanism. 110

During the return stroke of the soldering tool, the cam will turn through 60° to cause the different points of the cam to come successively in contact with the point of the contact arm 98. At the end of this period 115 the arm 88 of the soldering tool is at the same distance to the left of the shaft 87 as it is to the right in Fig. 17. The vertical position of the shaft 87 due to the movement of the cam 97, is also made so that the soldering tool is in contact with the post. As it moves along the hot iron immediately contacts with and melts the solder which is being fed forward as previously described. The continued contact of the notched tool 120 and post gives a good soldered connection between the zinc can and post. When the arm 83 moves through 90° the can is in the central position in which the operation started and the cam 97 has moved through 125 130

During the remaining 240° of the cam rotation the same movements produced by the preceding 120° will be twice repeated.

It is found that six prongs is the practical 5 minimum for the star wheel although eight, ten, etc., could be used, in which case the rates of rotation of shafts 82 and 62, and part of arm 86 would have to be changed accordingly.

10 By the term self fluxing solder, I refer to any of the well known soldering materials which require no acid treatment of the metal to cause the solder to adhere. It will be evident, however, that acid or other fluxing compound could be applied by a brush arrangement similar to that used for scratching the cans.

15 To loosen any cells which may be slightly soldered to the horn, as previously mentioned, a blow is delivered to each cell by the hammer 103. In the position shown in Fig. 22 the horn 26 forces back this spring hammer by engaging the sloping side 118. As the cell advances the hammer is released 20 and delivers a blow to the end of the can with sufficient force to loosen the cell.

25 The cells are finally picked from the holder by the fingers 108 of the rotating drum and delivered to the twister. The 30 chain drive 105 keeps the conveyer and drum in proper relation and assures the delivery of a single cell to each sector. As each cell is delivered into the twister it forces all of the cells forward and finally 35 delivers them to the moving platform in a vertical position.

40 While in this position on the moving table, the cells may have various operations performed on them. For example, disks, sand, sealing compound, knurls, etc., may be applied, all without the use of trucks.

Having described my invention, what I claim is:—

45 1. In apparatus for operating on a dry cell, a conveyer having means thereon for supporting dry cells, means for abrading a spot on said cells and a lifting member adapted to engage said supports and cells to raise the cells.

50 2. In apparatus for operating on dry cells, a conveyer chain comprising a plurality of carrying strips having means adapted to support a dry cell, abrading means, and a lifting member adapted to engage said carrying strips and cells near one end thereof, whereby one end of each cell is raised successively to engage said abrading means.

55 3. In a conveyer for dry cells, a plurality of horizontal carrying strips, a pair of notched supports attached to each strip adapted to receive and aline a dry cell with one of said carrying strips, an upwardly projecting member attached to each strip adapted to coöperate with the dry cell can 60 to support a binding post, means for con-

necting the strips together, a track, and means for moving the strips along said track.

4. A holder for horizontally placed cells, 70 consisting of a plurality of notched supports, a section of a chain conveyer adapted to receive said supports, and an upwardly extending arm projecting from the conveyer section having a notch adapted to receive a binding post for a cell. 75

5. A holder for dry cells consisting of front and rear notched supports adapted to carry a cell in a horizontal position, a carrier for said supports, means permitting the carrier to be connected as a section of a 80 chain conveyer and to engage a driving mechanism, and an arm projecting upwardly from the carrier beyond the supports and adapted to receive a binding post for a cell.

6. A holder for dry cell cans consisting 85 of a carrying strip, a plurality of lugs projecting from said strip and having holes therethrough, a plurality of pins adapted to be passed through the holes, said pins and holes permitting the carrying strip to be 90 connected as a section of a chain conveyer, a pair of notched supports attached to the strip and adapted to receive and aline a can, and an upwardly projecting member attached to the strip and adapted to coöperate 95 with a dry cell can to support a binding post when a can is fitted in the notched supports.

7. In apparatus for operating on dry cells, the combination of a holder for a dry 100 cell can, consisting of a carrying strip, an upwardly projecting member attached to the strip and adapted to coöperate with a dry cell can to support a binding post when a can is fitted in the holder, a plurality of 105 lugs projecting from said strip and having an opening therethrough, a plurality of rollers adapted to be fitted between said lugs, each roller having an opening in alinement with the lug openings, a plurality of pins 110 adapted to be passed through the openings and constituting connecting means whereby the holder may be inserted as one member of a chain conveyer, a track for said rollers, means adapted to move the carrier along 115 the track and means for removing a can from the carrying strip.

8. In apparatus for operating on dry cells, a conveyer chain comprising a plurality of strips having means adapted to 120 support a dry cell can, upwardly projecting members adapted to receive a dry cell post attached to said strips at one end, means for moving the cans toward said projecting members, abrading means, a lifting member 125 adapted to engage said supporting strips and cans near one end thereof whereby one end of each cell is raised successively to engage the abrading means.

9. In apparatus for operating on dry 130

8
cells, a conveyer having supports adapted to carry dry cell cans in a horizontal position, an abrading wheel adapted to be placed in contact with a spot at the open end of the can, upwardly projecting members attached to the supports adapted to coöperate with the can at the abraded spot to carry the binding post, a soldering iron adapted to contact with the binding post at the abraded spot, and means for moving the soldering iron in the direction of movement of the conveyer.

10. In apparatus for operating on dry cells, a conveyer having a plurality of supports adapted to hold dry cell cans in a horizontal position, a shaft having a plurality of projections adapted to be successively engaged by the supports to rotate the shaft, a soldering iron mounted on a second shaft, means for transferring the rotary movement of the first shaft into reciprocating

movement of the second shaft, a cam on the first shaft adapted to raise and lower the second shaft, a reel of solder and means operated from the first shaft for feeding solder from said reel into contact with the soldering iron.

11. In apparatus for operating on dry cells, a conveyer having a plurality of supports adapted to hold dry cell cans in a horizontal position, means for abrading a spot at the open end of the cans, an upwardly projecting member attached to the supports adapted to coöperate with the cans at the abraded spots to hold a binding post, a soldering iron adapted to be placed successively in contact with the abrading spots and posts, and means for feeding solder against the soldering iron.

In testimony whereof I hereunto affix my signature.

J. C. GILLETTE.
